UNITED STATES PATENT OFFICE.

JOSEPH R. BOWERS, OF CONCORD, NEW HAMPSHIRE.

BRICK-PRESS.

SPECIFICATION forming part of Letters Patent No. 316,939, dated May 5, 1885.

Application filed January 5, 1885. (No model.)

To all whom it may concern:

Be it known that I, JOSEPH R. BOWERS, of Concord, in the county of Merrimac, State of New Hampshire, have invented a certain new and useful Improvement in Brick-Presses, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved brick-press; Fig. 2, a top plan view of the same, and Fig. 3 a vertical longitudinal section.

Like letters of reference indicate corresponding parts in the different figures of the drawings.

My invention relates to that class of brick-presses which are employed in finishing or "facing" the brick; and it consists in a novel construction and arrangement of the parts, as hereinafter more fully set forth and claimed, by which a more effective device of this character is produced than is now in ordinary use.

The nature and operation of the improvement will be readily understood by all conversant with such matters from the following explanation.

In the drawings, A represents the bed-piece or body of the machine, which is rectangular in form, and provided at one end with the legs B B, and near its opposite end with the trucks C C.

Projecting upwardly from the body A, and at either side thereof, above the leg B, there is a standard, D, carrying a friction-roller, E.

A standard, H, is disposed at either side of the body A, nearly over the axle of the trucks C, and connecting these standards there is a cross head or bar, J.

Two standards, K, are arranged nearly midway between the standards H D at the center of the machine, the last-named standards being connected by the cross head or bar L.

A main frame-work, rectangular in form and consisting of the side rails, M M, and end rails, N Q, is disposed on the upper portion of the machine, said frame-work resting on the friction-rollers E, and proper supports or ways (not shown) on the standards H K being adapt-

ed to move back and forth on said supports, when reciprocated, as hereinafter described.

Journaled in the upper portions of the standards K there is a toothed segment, O, adapted to intermesh with a corresponding toothed segment, P, which is journaled at x near the end rail Q of said frame-work.

Projecting upwardly from the rails M, at either side of the machine, there is a standard, R, and journaled horizontally at m in the upper portion of these standards there is a rocker-shaft, S, provided with a short arm, T, and lever U, arranged nearly at right angles with each other on said shaft, a portion of the lever being represented as broken off.

An auxiliary frame-work consisting of the side rails, v, and head-rail w, is fitted to slide in proper ways i on the inner faces of the side rail, M, being rendered adjustable laterally by the set-screws t.

A bar, Y, extends horizontally between the standards H H, and disposed thereon is a bed-plate or table, Z.

A cap-plate or bar, G, is disposed between the standards H above the table Z, being adapted to slide vertically between said standards, and rendered adjustable by the set-screws g.

A follower, h, is attached to the end rail N, and projecting horizontally from either end of the head-rail w there is a bar, d, these bars being arranged in parallelism and connected at their outer ends by the cross-bar b, carrying the face-plate f.

The matrix in which the brick is pressed is formed by the bed-plate or table Z, cap-plate or bar G, face-plate f, follower h, and standards H, or by vertical end pieces, (shown by the dotted lines k in Fig. 2,) which end pieces extend between the bar G and bed-plate Z, and are properly backed or supported.

Attached to the shaft l, on which the segment P is journaled, there is a downwardly-projecting curved arm or "kicker," n, adapted to engage a standard, F, at the end of the body A when said segment is depressed, as shown in Fig. 1.

The arm T has a cross-head, p, (see Fig. 2,) at its outer end, and is connected with the inner end of the segment O by the links or pitmen r.

In the use of my improvement the segment O P being depressed, the arm T in a horizon-

tal and the lever U in a vertical position, with the face-plate f advanced to the outer opening of the matrix, as shown in Fig. 1, the brick I is then placed on the bed-plate or table Z in front of the follower h and the lever U depressed to bring the parts into the position shown in Fig. 3.

As the segments O P are raised by depressing the lever U, the rectangular main frame-work will be moved in the direction of the standard F, causing the follower h to force the brick I into the matrix and push the face-plate f out of the matrix until the projections j on the rails v strike the standards K or bar L, thereby stopping the advance of the auxiliary frame, after which the main frame-work, consisting of the rails M N Q, continues to advance for a short distance as the lever U is further depressed, thereby forcing the follower h against the brick and the brick against the face-plate f in the matrix, and pressing or facing it in a manner which will be readily obvious without a more explicit description.

After the brick has been pressed as described, the lever U is elevated, permitting the segments O P to drop by gravitation and bring the curved arm n against the standard F, thereby "kicking" or forcing the main frame toward the standards H and withdrawing the follower h from the matrix, bringing the parts again into their normal position, as shown at Fig. 1.

Projecting inwardly from the inner face of either rail M M there is a stud or stop, s, and as the rectangular or main frame is pushed back by the curved arm n, as shown in Fig. 1, the studs s are brought into contact with the side rails, v, of the auxiliary frame, causing said frame to advance, and the face-plate f to force the pressed brick out of the matrix onto the table Z, from which it may be removed preparatory to repeating the operation.

One of the side rails, M, is curved downwardly at the end nearest the standard H, as shown at q, Fig. 3, thereby enabling the pressed brick to be readily removed from the table by slipping them endwise therefrom, which can be done to better advantage than to lift them vertically.

From the foregoing it will be obvious that the pressure on the brick by which it is faced occurs after the auxiliary frame is stopped by the standards K or bar L, at or about which time the parts have assumed the position shown in Fig. 3.

When the lever U is depressed and the segments O P are elevated, the pitmen or links r approach the center of motion m of said lever, thereby in effect shortening the arm T and greatly increasing the power of said lever, while at the same time the central axial lines of the segments O P, continuing to approach a

horizontal line drawn through their pivotal supports, the power exerted through the medium of the segments on the rectangular or main frame-work is greatly increased, the segments approaching a horizontal position, and the arm T a vertical position at the time when it is required to exert the greatest pressure on the brick.

The matrix may be increased or decreased in size, as desired, by raising or lowering the cap-plate G and changing the follower h, face-plate f, and end pieces, k, in accordance with the size of the brick to be pressed.

The trucks enable the press to be readily removed from place to place as required, and serve in place of legs to support one end of the machine.

By disposing the matrix at the end of the machine opposite the lever U the insertion and removal of the brick are greatly facilitated and room afforded for the proper operation of the other parts.

Having thus explained my invention, what I claim is—

1. In a brick-press, the combination, with a reciprocating frame or follower, of a shaft pivoted to said reciprocating frame and traversing therewith, a toothed segment fixed to said shaft, a shaft supported in fixed bearings on the machine, a toothed segment attached to the last-named shaft and intermeshing with the segment on said traversing shaft, upright standards attached to the reciprocating frame, a rock-shaft supported in said standards above said segments, a crank-arm on said rock-shaft, a pitman connecting said crank-arm with one of said segments, and an actuating-lever attached to said rock-shaft, the said parts being arranged substantially as described, whereby the pitman is caused to approach the center of motion of said rock-shaft when said segments are raised by the depression of said lever.

2. In a brick-press, the rocker-shaft S, provided with the lever U and arm T, in combination with the segments O P, pitman r, standards K, and a sliding frame-work having the standards R R and carrying a follower, substantially as set forth.

3. In a brick-press, the curved arm n, in combination with the segment P, standard F, and the sliding main frame-work, substantially as described.

4. In a brick-press, the rail M, provided with the curve q, to enable the brick to be removed from the table Z, substantially as described.

JOSEPH R. BOWERS.
